UNITED STATES PATENT OFFICE.

EDWARD S. HOUGH, OF OAKLAND, CALIFORNIA.

ENGINE FEED-WATER SUPPLY.

SPECIFICATION forming part of Letters Patent No. 608,679, dated August 9, 1898.

Application filed May 11, 1896. Serial No. 591,161. (No model.)

To all whom it may concern:

Be it known that I, EDWARD S. HOUGH, a citizen of the United States, residing at Oakland, in the county of Alameda and State of California, have invented certain new and useful Improvements in Engine Feed-Water Supply; and I do hereby declare the following to be a full, clear, and exact description of said invention, such as will enable others skilled in the art to which it most nearly appertains to make, use, and practice the same.

This invention relates to improvements in engine feed-water supply. The present invention consists in providing the supply-pipe near and outside the boiler with a spring-actuated valve.

In the drawings, Figure 1 is a diagram showing the position of the pump, boiler-supply pipe, and valve arranged in accord with this invention. Fig. 2 is a sectional elevation illustrating a spring-actuated valve adapted to be used in connection with the present invention.

For the purpose of description with reference to the drawings I will let the letter A designate the pump, which is shown as a plunger or a ram type of pump. The boiler is designated by the letter B and the supply-pipe connecting the pump and boiler by the letter C, both of the usual construction.

Placed on the supply-pipe C near the boiler is the valve D. The valve D is of any suitable construction of spring-actuated valves. By the term "spring-actuated valve" as used here is meant a valve which is raised from its seat against the pressure of a spring and which is returned to its seat by the said spring. In the form of spring-actuated valve here shown D' represents the valve proper, D³ the valve-stem, and D⁴ the spring.

When now the supply-pipe C is provided with a valve such as described, the action is as follows: The impulse given to the water by the pump raises the valve from its seat

against the spring-pressure, and the water 45 rushes through on its way to the boiler, the pressure therein being overcome by the force of the pump. As the pump reaches the end of its stroke its force is gradually diminished until finally suspended. At the instant the 50 pressure of the pump falls below the combined forces of the pressure of the boiler and the pressure of the spring the latter operates to seat the valve gradually against the then nearly stationary column of water. The 55 valve being thus closed, that part of the column of water between the boiler and valve does not recede after the suspension of the pump-pressure. There is, therefore, no backward rush of the column of water caused by 60 the boiler force, and consequently no pound or shock to the pipe or valve.

I am aware that certain forms of feed-water-heater supply-pipes have been provided with a spring-actuated valve located inside 65 the steam-space of the boiler at the end of the supply-pipe. I am also aware that various kinds of check-valves other than spring-actuated have been used on feed-water-supply pipes near the boiler, and I do not claim 70 such constructions.

Having thus described this invention, it is claimed—

In an engine feed-water supply such as described, the combination with a reciprocating 75 pump to supply water to the boiler against the pressure thereof, of a supply-pipe connecting the said pump and boiler, and a valve mounted on the said pipe outside and near the boiler, and provided with a spring to seat 80 it, substantially as described.

In testimony whereof I have hereunto signed my name, in the presence of two witnesses, this 30th day of October, 1895.

EDWARD S. HOUGH.
